UNITED STATES PATENT OFFICE.

GUY A. LYON, OF DETROIT, MICHIGAN, ASSIGNOR TO LONG MANUFACTURING COMPANY, OF DETROIT, MICHIGAN, A CORPORATION OF MICHIGAN.

HINGE CONSTRUCTION.

1,152,958.

Specification of Letters Patent. Patented Sept. 7, 1915.

Application filed November 20, 1912. Serial No. 732,418.

To all whom it may concern:

Be it known that I, GUY A. LYON, a citizen of the United States, residing at Detroit, in the county of Wayne and State of Michigan, have invented certain new and useful Improvements in Hinge Construction, of which the following is a full, clear, and exact description.

This invention relates to improvements in the construction of hinges and in the method of forming them and attaching them to the adjoining parts. In the particular form in which I have shown it, it is applied to the hood which is utilized to cover the motors of automobiles; and it is especially well adapted to such use, although it is, of course, to be understood that it is susceptible of use in a variety of other adaptations.

Among the objects of the invention are to provide a hinge construction that will be simple in assembling and shall be susceptible of convenient and quick attachment and detachment from the adjoining parts; also to enable the hinge to be fastened without rivets to the automobile hood referred to. The hinges may be put on the parts of the hood after the body part of the hood has been enameled and after the hinges have been enameled, if it is desired to enamel them, so that smoothness of the enameling is produced, which would not be the case were the hinges and body part enameled in their assembled state. Any subsequent turning of the hinges would then be liable to crack the enamel which adhered to the spaces between the hinges and the body part of the hood.

Other advantages will be apparent from the ensuing description, such as providing rigidity to the hood at the hinge-joint, flexibility of the position of the hinge-pin or rod, and a water-proof joint.

In the accompanying drawings Figure 1 is an end view of an automobile hood; Fig. 2 is a side elevation of a hood with one side opened, the open side lying in the position indicated by dotted lines in Fig. 1; and Fig. 3 is a sectional transverse view of the top hinge; Fig. 4 is a sectional transverse view of one of the side hinges; Figs. 5 and 6 are an end and front view respectively of a modified form of the hinge; Figs. 7, 8 and 9 are details showing the several parts of the top hinge illustrated in Figs. 1, 2 and 3;

and Figs. 10, 11 and 12 are details showing possible modifications.

Referring now to Figs. 1, 2 and 3; 10—10 indicate the top portion of the automobile hood and 11—11 the vertical portions thereof. The top portion of the hood is united in the center by a hinge wherein reside the present improvements.

As the two parts of the hinge are substantially identical I will, for convenience, describe one portion only in detail: A strip 65 of metal 13 is bent longitudinally at 14 so that the portion 15 is folded over into a position parallel with the other part of the strip, leaving a narrow space 16 between. The said other part is bent again at 17 so 70 as to form a flange 18 substantially perpendicular to the folded-over portion. Tubular hinge members 19, formed of strips long enough to encircle a hinge-pin 12 and leave projecting ends 20 and 21, are fastened at 75 intervals to the flange 18, the end 20 being inserted in space 16 and the end 21 riveted or otherwise united to the flange 18. The hinge members are placed in longitudinal alinement so that the hinge-pin 12 may be 80 passed through all of them. The strips from which the tubular members are formed are of such width, and the members are so positioned on the flange 18, that each may enter a space between two members on the 85 opposite part of the hinge. That is, they are arranged alternately from opposite sides so that the insertion of the pin 12 connects the two portions 10 of the body of the hood in a hinge-joint. This arrangement will be 90 well understood by reference to Fig. 2.

Each piece 10 of the hood is prepared to receive the hinge by its edge 25 being folded over into a position parallel with the adjacent part of the piece, leaving a space 26 between. The hinge is then attached to the piece 10 by being slipped into place longitudinally, the folded-over portion 25 being adapted to slip into the space 16 while the folded-over portion 15 of the hinge slips 100 into the space 26. When thus united the hinge is attached to the piece 10 by an interlock which secures it firmly in place, but leaving the outside of the hood smooth.

While friction alone is practically sufficient to insure the hinge retaining its longitudinal position with reference to the parts 10, they may be further secured by conical

depressions 27 made with a center punch which, as indicated in Fig. 3, forces portions of one member into depressions in the adjacent member. It is not essential that the tubular members 19 be formed of pieces separate from the strip 13, as they may be integral therewith as clearly shown in Fig. 10. Neither is it essential that the flange 18 be used, although this flange in itself has certain advantages. Fig. 11 shows the tubular member 19 integral with the strip 13 and the flange 18 omitted. Furthermore, it is not essential for one end of the tubular member to be inserted in the space 16, Fig. 12 showing a construction wherein this is dispensed with. It will be observed, however, that in the construction shown in Fig. 12 the neck which connects the tubular member 19 to the strip 13 passes across the space 16, leaving only sufficient space to receive the bend of the hood 10. In Figs. 3, 10 and 11 the arrangement is similar, except that room is left to receive both the hood and the end 20. This helps to give firmness and rigidity to the structure.

The side pieces 11 are united to the top pieces 10 by a somewhat modified form of hinge, but in which some of the main features of the hinge already described are embodied. The construction of the hinge by which the side pieces are attached is well illustrated in the Fig. 4 where as will be seen, the folded-over portion 30 corresponds with the folded-over portion 15 leaving a space similar to space 16. In like manner the pieces 10 and 11 have folded-over portions 32 corresponding to the portions 25 already described. In the construction shown in Fig. 4, however, it is not necessary to slip the hinge part into place longitudinally as the tubular members do not prevent them entering laterally. After being placed they may be secured as already described, with a center punch. Figs. 5 and 6 illustrate the same form of hinge with the parts secured in another manner. In this construction a notch is cut in the strip 31 and the edge of the folded-over part 32 is cut loose so it may be bent outward and over the part 31 of the hinge as at 33 Figs. 5 and 6. A similar operation being performed at each end of each part of the hinge will prevent either lateral or longitudinal displacement.

The flange construction already described adds very much to the rigidity of the hinge, which is of especial value on the top of the hood. These opposite flanges adjoin each other and abut one against the other when the body portions of the hinge are in their normal closed position. The hood parts and hinge parts may be made complete, including their final finish, whether enameled, polished or plated, and assembled afterward without injury to the finish. This feature

offers considerable advantage in the way of avoiding some of the difficulties in such work, and if it is desired to make the finish of the hinge dissimilar to that of the hood, this may be done without the difficulties such a proceeding would ordinarily involve.

It will thus be apparent that from the construction heretofore described, the hinge may be very readily assembled or taken apart. The hinge elements are arranged alternately so that the passing of the hinge-pin through the successive alternate sections unites the two portions of the hood by a hinge-joint. As stated, these hinge sections may be formed from one piece but they form part of an intermediate member which is quickly attached to or detached from the body portion of the hood. That is, this intermediate member carrying the tubular portions of the hinge, can be quickly hooked in under the corresponding portion of the hood somewhat as two opposite portions of a buckle would be clasped together. Then with the hinge-pin in place, the intermediate member is retained in its location either by friction against the body portion of the hood or by the center punch depressions 27 heretofore referred to. It will also be observed that with this construction, the hinge-pin may be elevated above the hinge as shown at the top hinge in Fig. 1, and elevated to any desired height, or it may be reversed and located within the interior as shown on the side hinges in Fig. 1. This gives flexibility of location of the hinge-pin. The side hinge also affords a very effective water-proof hinge, the outer wall of the hood presenting a smooth surface appearance and making it very difficult for any water to penetrate into the interior of the hood.

While I have shown and described the preferred embodiment of my invention and certain modifications thereof, I am aware and wish it understood that other modifications may be made without departing from the substance of or exceeding the scope of the appended claims, and of course, these improvements are applicable to various uses as to hinge constructions in general.

What I claim is as follows:

1. A hinge construction for connecting two opposite body portions, comprising a body portion having a hook-shaped formation, a separate member having a corresponding hook-shaped formation to clasp into the hook of the body portion, said member having a portion bent into tubular form to receive a hinge pin, the portion so formed being of such length as to complete the tube and leave a surplus to be tucked into the hook on said separate member.

2. A hinge construction comprising two opposite body portions, each having a hook-shaped formation at the adjacent edges, a

separate member for each body portion, each of which has a corresponding hook-shaped formation to clasp into the hook of its body portion, said members having alternate and opposite hinge sections to receive the hinge-pin; flanges formed on each of said members where they will be adjacent to each other when the body portions are in normal position; and a hinge-pin to engage these opposite sections and thus connect said two opposite body portions with a hinge-joint.

3. In a hinge for metal parts, a strip of metal having a longitudinal bend which folds one edge of the strip into a position opposite to and parallel with the strip and separated therefrom by a narrow space, said strip being bent to form a flange substantially perpendicular to the aforesaid parallel parts; and tubular hinge members extending from said flange in longitudinal alinement with each other and adapted to receive the hinge-pin.

4. In a hinge for metal parts, a strip of metal having a longitudinal bend which folds a portion of the strip into a position opposite to and parallel with the strip and separated therefrom by a narrow space, said strip being bent to form a flange substantially perpendicular to the aforesaid parallel parts; and tubular hinge members formed of strips long enough to encircle a hinge-pin and leave projecting ends, one of said ends on each strip being secured to the flange, with the other end inserted in the aforesaid space, the hinge members, being thereby mounted in longitudinal alinement and adapted to receive the hinge-pin.

5. In a hinge for metal parts, a strip of metal having a longitudinal bend which folds a portion of the strip into a position opposite to and parallel with the strip and separated therefrom by a narrow space; and tubular hinge members extending from said strip in longitudinal alinement with each other and adapted to receive the hinge-pin, said members being so placed with reference to the aforesaid space that the neck by which they are attached to the strip passes across the entrance to the space.

50 6. A construction for forming and attaching hinges to metal parts comprising: a pair of metal strips each having a longitudinal

nal bend which folds a portion of the strip into a position opposite to and parallel with the strip and separated therefrom by a narrow space, said strip being bent to form a flange substantially perpendicular to the aforesaid parallel parts; tubular hinge members formed of strips long enough to encircle a hinge-pin and leave projecting ends, one of said ends on each strip being secured to the flange, with the other end inserted in the aforesaid space, the tubular members being in such position with reference to the flange that the part thereof which attaches to the flange passes across the entrance to the aforesaid space, the members secured to each strip being of such width and so positioned that they may enter spaces between and assume longitudinal alinement with the hinge members on the other strip, and a hinge-pin which, passing through the several members, unites the two strips; and folds formed on the articles to be united by the hinge similar to and with which the folds on the hinge may interlock, the folded-over part of each entering the space under the folded-over part of the other.

7. A construction for forming and attaching hinges to metal parts, comprising: a pair of metal strips each having a longitudinal bend which folds a portion of the strip into a position opposite to and parallel with the strip and separated therefrom by a narrow space, each strip having tubular hinge members extending from said strip in longitudinal alinement, said tubular members consisting of laterally extending circumflected projections whose ends are tucked into said narrow space, the tubular members on each strip being of such length and so positioned that they may enter spaces between and assume longitudinal alinement with the tubular members on the other strip; and a hinge-pin which, passing through the several members unites the two strips.

In testimony whereof I affix my signature in the presence of two subscribing witnesses.
